UNITED STATES PATENT OFFICE.

PHILIP T. DODGE, OF BROOKLYN, NEW YORK, ASSIGNOR TO MERGEN-
THALER LINOTYPE COMPANY, A CORPORATION OF NEW YORK.

LINOTYPE-MACHINE.

SPECIFICATION forming part of Letters Patent No. 790,348, dated May 23, 1905.

Application filed September 1, 1904. Serial No. 223,008.

To all whom it may concern:

Be it known that I, PHILIP T. DODGE, of Brooklyn, county of Kings, and State of New York, have invented a new and useful Improvement in Linotype-Machines, of which the following is a specification.

My invention has reference to the Mergenthaler linotype, such as shown in United States Letters Patent No. 436,532, and analogous machines wherein a melting-pot is arranged to deliver molten metal through a perforated or slotted mouth into a slotted mold and against a series of matrices assembled temporarily against the face of the mold for the purpose of producing a linotype or printing slug. In these machines it is necessary that the flat mouth of the melting-pot shall fit closely against the flat back of the mold in order to close the mold and prevent the leakage or overflow of metal between them, the metal being delivered under substantial pressure. Heretofore the melting-pots have been mounted to swing on horizontal pivots or to move on horizontal guides to and from the mold or the mold mounted to slide to and from the pot, the parts being in every instance positively and accurately guided with the idea of maintaining their faces parallel with each other under all conditions. In practice it has been found that, owing to the repeated and unequal heating and cooling of the parts and other causes, the mold and the mouth of the pot are liable to lose their alinement or parallelism, and in consequence of this fact it was frequently necessary to dress or refinish the mouth of the pot or readjust the parts in order to insure a close union with the back of the mold.

The object of my invention is to overcome this difficulty; and to this end it consists, broadly, in so mounting the pot having a flat mouth to fit directly against and close a flat mold that it may rock or turn horizontally in order that its mouth may adjust itself tightly to the back of the mold. The means for supporting the pot and for moving the same to and from the mold, if of the movable type, may be modified at will, provided only the pot is supported at the proper level and ar-

ranged to rock or turn horizontally in the 50 plane of the length of the mold to an extent sufficient to insure close contact of its mouth with the mold when the two are brought together.

In the accompanying drawings I have shown 55 the invention embodied in its preferred form in the commercial Mergenthaler linotype-machine of the present day.

Referring to the drawings, Figure 1 represents a plan view of the pot with the top of 60 the jacket or casing removed, the mold being shown in outline. Fig. 2 is a vertical section from front to rear on the line 2 2 of the preceding figure through the pot and the mold. Figs. 3, 4, and 5 show alternative construc- 65 tions.

Referring to the drawings, A represents the pot or crucible, in which the supply of type-metal is maintained in a molten condition by means of a flame thereunder. It is constructed with a delivery-throat a and with a mouth-piece a', having a flat outer surface adapted to close tightly against the rear face of the mold B and with a row of perforations therethrough for delivering the metal into the 75 mold-cavity or mold proper. This pot is also provided with a vertical cylinder or well a'', communicating with the delivery-throat and containing a mechanically-actuated plunger C, by means of which the forcible delivery of 80 the metal is effected.

D represents a supporting jacket or frame, in which the pot or crucible is sustained and by which it is moved to and from the mold. The jacket is provided with supporting-legs 85 d, mounted to rock on a fixed horizontal axis E, this arrangement permitting the jacket and the contained pot to swing forward and backward to and from the mold B under the influence of an operating-cam. 90

So far as described the foregoing parts are of the ordinary construction and operate in the ordinary manner.

Heretofore the pot or crucible has been secured rigidly in place within the sustaining-jacket, and the alinement of the mouthpiece a' with the mold has been effected by adjusting the legs d on their supporting-pivot E by

means of intermediate screws and other devices, which are now omitted. In carrying my invention into effect I support the crucible A loosely within the jacket, so that it may turn 5 or rock horizontally in the plane of the length of the mold. In the preferred form shown in the drawings the weight of the pot is sustained by three ears or studs a^4 a^5 a^6 formed on its upper end and seated loosely in cavities in the 10 upper part of the jacket D. The jacket D is provided with a top or lid d^2 , secured rigidly to the lower portion. This lid carries a vertical stud or pivot-pin F, which projects downward into a corresponding seat in the top of 15 the pot A, forming the center or axis about which the pot may turn within the jacket to a limited extent. This pivot F is preferably made of hardened steel, with its upper end seated tightly in the cap and secured by a screw 20 f ; but it may be made in any other suitable form. In order to reduce the friction between the pot and the sustaining-jacket, balls G may be inserted between the supporting-ears of the pot and the upper part of the jacket, as shown; 25 but they are not of the essence of the invention.

While it is preferred to arrange the pot to rock about a pivot, as above described, it may be mounted to rock on a V-shaped or equivalent support F' at the rear side, as shown in 30 Fig. 4, or, as shown in Fig. 3, a series of balls or vertical rollers F² may be seated around the cylindrical portion of the pot and against the inner circular wall of the jacket.

The jacket containing my oscillating or self-adjusting pot instead of being mounted to rock on supporting-legs may be arranged to slide forward and backward on fixed horizontal guides I, as indicated in Fig. 5. This method of supporting the pot is old in the art and is 40 not claimed as a part of my invention.

The form of jacket or support, the manner of sustaining the same, the form of the pot, and the connection between the pot and the jacket all may be modified at will, provided 45 the flat-faced mold and flat-faced pot and the

coöperating parts retain a mode of action essentially such as herein described.

Having described my invention, what I claim is—

1. In a linotype-machine, the combination 50 of a slotted mold having a flat rear face, a metal-pot having a flat mouth adapted to directly close the back of the mold and deliver metal thereto, and a support wherein the pot is free to turn in the plane of the length of the mold, 55 substantially as described, whereby the mouth of the pot is permitted to assume automatically a proper alinement against the rear face of the mold.

2. In a linotype-machine, a pot, having an 60 elongated flat mouth and mounted to turn freely in the plane of the length of its mouth, in combination with a flat mold arranged to coöperate directly with and to be closed by the mouth of the pot and to receive metal 65 therefrom.

3. A pot for a linotype-machine, comprising a jacket or support, a pot proper having an elongated flat-faced mouth, and intermediate connections permitting the pot to turn 70 freely in the jacket in the direction of the plane of its length.

4. In a linotype-machine, the combination 75 of the following elements: a slotted mold having a flat rear face, a pot having a flat mouth adapted to close tightly against the mold to close the same and to deliver metal thereto, a pot-support movable in a horizontal direction to and from the mold, and intermediate connections between the support and the pot permitting the latter to turn in the plane of the 80 length of the mold.

In testimony whereof I hereunto set my hand, this 31st day of August, 1904, in the presence of two attesting witnesses.

PHILIP T. DODGE.
